UNITED STATES PATENT OFFICE.

HENRY H. MORETON, OF STONY POINT, NEW YORK, ASSIGNOR, BY MESNE ASSIGNMENTS,
TO MORETON CARBURETER CORPORATION, OF NEW YORK, N. Y., A CORPORATION OF
NEW YORK.

SPARKING DEVICE.

1,257,291.

Specification of Letters Patent. Patented Feb. 19, 1918.

Application filed July 13, 1914. Serial No. 850,768.

To all whom it may concern:

Be it known that I, HENRY H. MORETON, a citizen of the United States, residing at Stony Point, in the county of Rockland and State of New York, have invented new and useful Improvements in Sparking Devices, of which the following is a specification.

This invention relates to a sparking device capable of use for ignition purposes, or in connection with any form of apparatus which, in operation, requires the passing of an electric spark between separated terminals.

One of the objects of the invention is to provide a more intense spark than has heretofore been possible for a current of given value. A further object is to provide means for increasing the number of sparking points without decreasing the intensity of the current at any of the sparking terminals and without necessitating an increase in current to maintain the same. A further object is to provide a sparking device which will be simple in construction and efficient 25 in operation as an ignition device for explosive engines, and the like.

The invention will be hereinafter fully set forth and particularly pointed out in the claims.

30 In the accompanying drawing:—

Figure 1 is a side elevation of a spark plug embodying my invention. Fig. 2 is a longitudinal sectional view thereof. Fig. 3 is a similar view illustrating a slight modification. Fig. 4 is a transverse sectional view on the line 4—4, Fig. 2.

Referring to the drawing, 10 designates an insulating block of any suitable material, such as mica, porcelain, or the like, and passing longitudinally through said insulating block is a central electrode or conductor 11, one end of which projects beyond the end of the insulating member to form a sparking terminal, as indicated at 12. If desired, the other end of the conductor 11 may be threaded to form a binding post, as indicated at 13, by means of which the terminal 14 of an electrical conductor 15 leading from a suitable source of electricity, may be connected with said conductor 11. The insulating block 10 is carried by a supporting bushing 16, in any suitable manner. In the drawing I have illustrated said insulating block as provided with an annular rib or shoulder 17 resting upon a correspond-

ingly shaped shoulder formed in the inner wall of the bushing, the bushing and insulating block being held together by a screw plug or packing nut 18. Suitable packing 19 is provided to maintain a gas tight joint. 60 The exterior of the bushing 16 is screw threaded to permit it to removably engage a correspondingly threaded opening in the wall of an engine, or the like. Secured to the end of the insulating block contiguous 65 to terminal 12, is a bridge member 20 comprising an annular body provided with a central opening 21 corresponding in diameter to the diameter of the insulating block 10, and into which the end of said block 70 extends. Said bridge member is preferably provided with an annular flange 22 which is secured to the insulating block in any suitable manner, to prevent relative movement 75 of the bridge member and the insulating block. In the end of the bushing 16 I secure pins 23 which extend opposite the bridge member but do not contact therewith, thus providing a spark gap between each pin and the bridge member. The number 80 of pins may be varied at will, although I have illustrated four pins equally spaced with respect to each other.

In operation, the sparking device receives its current through conductor 15, the bushing 16 being grounded in the usual manner. As the current passes through the conductor 11 sparks will pass from the terminal 12 to the bridge member 20. The opening 21 forms an annular chamber around the terminal 12 and the spark may jump in any direction, the normal intensity thereof being unimpaired. As soon as the spark reaches the bridge member 20 it passes over the surface thereof and will jump from said 95 bridge member to at least two of the pins 23 forming an intense spark in each instance, and from the pins passes to ground. Thus, a spark plug such as illustrated, when placed within an engine cylinder, will insure ignition of the explosive mixture within said cylinder by reason of the double sparking that is effected by means of the bridge member. It will be noted that the opening or chamber 21 is of such dimensions that the 100 current will not be short circuited, except under extreme conditions, but even if it should become short circuited sparks will 105 pass from the bridge member to the pins 23.

In Fig. 3 I have shown a slight modifica- 110

tion which consists in duplicating the bridge member. In other words a second bridge member 30 is interposed between the bridge member 20 and the bushing 16, and said bridge member 30 is provided with pins 31 forming gaps for the current passing from the bridge member 20. In this form of the invention the spark passes from the terminal 12 to bridge member 20, then jumps the gaps between said bridge member and the pins 31 of the bridge member 30, and finally from the latter to the bushing 16. In this manner three distinct sparking points are provided, and it is obvious that any number of sparking points may be obtained by increasing the number of bridge members.

It will be understood that while I have illustrated and described my invention as applied to an ignition device, I do not desire to limit myself in this particular, as the invention is capable of use in connection with any form of apparatus in which a multiplicity of sparking points may be desirable.

Having thus explained the nature of my invention, and described an operative manner of constructing and using the same, although without attempting to set forth all of the forms in which it may be made, or all of the forms of its use, what I claim is:—

1. A sparking device of the character described comprising an insulating block, a central electrode extending therethrough, a plurality of grounded electrodes arranged around said insulating block, and substantially parallel with the axis thereof, and a bridge member secured to one end of the insulating block and having a central recess to receive the contiguous end of said central electrode, said bridge member also having a flat face extending transversely of the block and positioned opposite to the sparking terminals of all of said grounded electrodes, for causing independent sparking at the terminals of all of the electrodes.

Copies of this patent may be obtained for five cents each, by addressing the "Commissioner of Patents, Washington, D. C."

2. A sparking device of the character described comprising an insulating block, a central electrode extending therethrough, a plurality of grounded electrodes arranged around said insulating block and substantially parallel with the axis thereof, and a bridge member having bars secured to one end of the insulating block and having a central recess to receive the contiguous end of said central electrode, said bridge member also having an annular flange extending transversely of the insulating block and provided with a flat face positioned opposite to the sparking terminals of all of said grounded electrodes, said bridge member being spaced from the central electrode to form an independent spark gap.

3. A sparking device comprising an insulating block, a central electrode extending therethrough, a plurality of grounded electrodes arranged around said insulating block, a bridge member secured to the insulating block and having a flat face disposed opposite said grounded electrodes to form a plurality of spark gaps, said bridge member being also provided with a plurality of electrodes, and a second bridge member secured to one end of the insulating block and having a central recess to receive the contiguous end of said central electrode, said bridge member also having a flat face disposed opposite the electrodes of the first bridge member to form spark gaps, the first bridge member being interposed between the second bridge member and the first mentioned grounded electrodes.

In testimony whereof I have hereunto set my hand in presence of two subscribing witnesses.

HENRY H. MORETON.
